UNITED STATES PATENT OFFICE.

OROS CO. C. WOOLSON, OF NEW YORK, N. Y.

CLINKER GRINDER AND DISCHARGER FOR FURNACES.

1,086,880.

Specification of Letters Patent.

Patented Feb. 10, 1914.

Application filed February 8, 1913. Serial No. 747,004.

To all whom it may concern:

Be it known that I, Orosco C. Woolson, a citizen of the United States, residing in New York city, in the county of New York and State of New York, have invented certain new and useful Improvements in Clinker Grinders and Dischargers for Furnaces, of which the following is a specification.

10 This invention relates to improvements applicable to that well-known class of furnaces from which the ashes and clinker are discharged downwardly through an extended longitudinal outlet space by the action of 15 a revoluble clinker-grinding shaft or member by which the discharge is effected and regulated.

A principal object of the present improvements is to furnish a clinker-grinder or dis- 20 charger in which a plurality of grinder members are so organized in connection with retaining and actuating devices that the grinder may be readily dis-assembled and reassembled, and that in case of overheating 25 or being blocked by hot slag and partial fusion, (these being accidents always imminent) the apparatus can be rapidly and economically dismantled and then be quickly put into operation again.

30 A further object is to furnish a clinker- grinder of that class in which a tubular grinder-shaft shall be composed of removable short-length members arranged for being driven one from another, and for being 35 cooled while in use by internal air currents.

In the drawing accompanying and forming a part of this specification, Figure 1 is a side view--in which some parts are partially broken away--of a clinker-discharger 40 organized and arranged in accordance with my present invention. Fig. 2 is a view from the left hand in Fig. 1 of the actuating lever and ratchet devices for rotating the clinker grinder. Fig. 3 is an end view seen 45 from the left hand in Fig. 1 of one of the grinder members; and Fig. 4 is an enlarged side view of a portion of this grinder member which, in Fig. 1, extends between two successive bearings near the forward end of 50 the furnace chamber. Fig. 5 is a cross sectional view in line X—X, Fig. 1, for illustrating the usual and preferred arrangement of the clinker grinder relatively to the inclined grate bars of the furnace. Fig. 6 55 is a side view, and Fig. 7 an end view, of one of the collar-form grinder members of

the style shown in the rearward portion of the grinder-shaft which is at the right hand in Fig. 1. Fig. 8 is a sectional view of the rear carrier in about the line Z—Z, of Fig. 1, for showing the manner in which the nut for the tension rod may be arranged in that carrier. Fig. 9 is a fragmentary view illustrating the preferred manner of connecting the rearward carrier and the forward carrier by means of a winged bar which is also a tension member; in this view both of the carriers are shown partially broken away and the tension nut at the left hand is shown in section. Fig. 10 is a front view of the 60 preferred form of tension nut, and is drawn in alinement with this part as shown in Fig. 9. Fig. 11 is a sectional view similar to the central portion of Fig. 5 for illustrating a modified form of the combined guide-bar 75 and doweling member which in Fig. 1 is shown in the form of a cylindrical tube. Fig. 12 is a side view of the forward end of the cylindrical form of guide-bar, and Fig. 13 is a view of the rearward end of the same 80 form of bar when this bar is arranged to also serve as the tensioning member. Fig. 14 illustrates a modification of the tubular guide-bar constructed for operating in connection with the rear carrier when this is 85 constructed as shown in Figs. 1, 8 and 9.

Similar characters designate like parts in all the figures.

In my improved clinker-grinder, a principal feature is the composite tubular grinder 90 shaft provided with breaker prongs or teeth and equipped for being revolved in bearings located at the bottom of the furnace; it is adapted for being employed in furnaces of various specific constructions and arrangements. In the drawings, however, I have shown only such fragmentary portions of one of the more usual forms of such furnaces, as seemed desirable for properly illustrating the arrangement and operation of 95 the grinder itself. In this selected form and arrangement, as shown in Fig. 5, the grinder shaft,—designated in a general way by S,—may be located between the two side walls, 2, 2¹, of the bottom frame F, which serves for 100 carrying the lower ends of the oppositely-inclined grate-bars, as g and g¹, in a well-known manner. For supporting the grinder S in the frame F, this may be provided with some suitable bearings, properly located, as for instance (see Fig. 1) the forward bearings b and b¹, the rear bearing b², 105

and a suitable number of intermediate bearings, as b^2 , b^3 ; this arrangement of frame and bearings being similar to some which are already well-known in this art, will be understood without a more particular description.

The grinder S is shown composed, in the present instance, (see Fig. 1) of the forward hollow driver-carrier B, the hollow rear carrier C, and a plurality of hollow grinder-members extending from the carrier B to the carrier C, and thereby forming a continuous composite shaft or grinder of a tubular character. The forward carrier B is shown supported in the bearings b and b^1 , and in practice will be suitably protected from above; for this purpose one of the furnace-plates may be arranged over the carrier, so indicated by the fragmentary portion of a cover-plate shown at 3. At the rearward end of the grinder, the rear carrier C is shown supported in bearings b^4 and b^5 , over which is located the cover-plate 27 for protecting the rear bearing and carrier from ashes and cinders. The said furnace plate is usually arranged in connection with the rearward brick wall, as 28, of the furnace chamber, while the space rearward of the member 27 may be conveniently filled in with concrete, as at 29, in a well known manner. In practice the said lower bearings (as from b^1 to b^4 , inclusive) may properly be arranged from one to two feet apart, depending, of course, on the size of the grinder and the length of the furnace. It will be noted that the preferred arrangement of the bearings is such that the driver-member B and the rear carrier member C, are supported independently of each other, both before and after grinder-shaft is assembled into working position. The concrete filling 29, may be employed for locating the end portion of a draft-conduit, as 30, leading to the smoke stack or chimney, or to a suction-flue, (not shown) whereby a suitable air circulation may be secured from the suction or draft of the chimney flue. The portion 30 of such draft pipe is indicated in the drawing as being an elbow of usual form, and this is shown carrying the fixed tube 30^a which connects through the rearward tubular bearing of the carrier C and through the interior spaces 5^a of the enlarged portion 5 of said carrier, with the interior of the grinder S. By comparing the construction of the rearward carrier C as shown in longitudinal section in Figs. 1 and 9, and in cross section in Fig. 8, it will be evident how the concentrically-located nut 5^b is upheld in the interior of the carrier by radial portions 5^c, around which the air currents may readily pass, as indicated by the arrows in Figs. 1 and 9.

For operating the grinder, any convenient means may be employed, preferably such as

commonly used in this art for similar purposes. One form of such an apparatus operatively carried on the driver-member B, consists of the lever L, herein shown formed of the two plates 6 and 6^a, suitably connected together and mounted in journals formed on the usual ratchet-wheel 8. A suitable pawl, as 7, is shown (Fig. 2) for engaging in the teeth of the ratchet-wheel, which is shown carried by the squared end portion 9 of the forward driving member B of the grinder apparatus. Forward of the ratchet-wheel a collar J is shown removably-fixed on said squared portion 9, and this part (to be made of any suitable length,) is shown extending outwardly at 10 for receiving a wrench, whereby the attendant may operate the grinder shaft S by hand-power whenever this becomes desirable. The lever L, of course, will be given the usual oscillatory movement, preferably by a reciprocating rod (not shown) connecting with the lever-pin 6^b, in a well-known manner.

At its forward end the clinker grinder S, as shown at the left hand in Fig. 1, is arranged to connect with and be driven from the forward carrier or driver-member B. For this purpose the rearward end of said carrier B,—which is the driving member of the apparatus,—is shown provided with transverse engaging driving faces at 4 for locking with corresponding engaging driving-faces, preferably the side faces of a projection 4^a, as illustrated in Figs. 1, 3 and 4, whereby the turning of the tubular driver-member B operates to rotate or drive the forward grinder member D, as if these two parts were one connected tubular shaft. These two parts B and D are shown engaging together above the aforesaid bearing b^1 , while the rearward end of the member D rests on the similar bearing b^2 . In a similar manner, the grinder members D and D^a connect together, preferably over the bearing b^3 , by the projection 4^b on one of them fitting into the recess 4^c of the other, thus forming a driving interlock or engagement. In an analogous manner, in this preferred form of my improvement, the rotative force from the driver B is transmitted through all the grinder members to the rear carrier C. The foregoing driving engagements, are shown so arranged that the locking faces at 4, 4^a, and at 4^b, 4^c, are all parallel, or in one direction, so that by turning the grinder until these faces stand vertically, the grinder member D may be lifted out of place, without requiring the driver B to be first drawn forward; but of course any rod or bar within the grinder-shaft, must first be removed. This arrangement of said driving faces, thus provides for disassembling the mechanism in a manner not otherwise available. To perform this work the workmen will usually enter the furnace chamber

130

(this being usually of ample size therefor) and by means of hooks or chains, lift up and remove the required member or members D, and will thus be able to make repairs to the best advantage.

In some instances it is desirable to disengage the driver B by sliding it forward a limited amount in its bearings. For this purpose I provide a shiftable driver-retainer device, which in this instance is indicated as being of the form of a clamp-collar, as 14, (Fig. 1.), which I prefer to make in two parts held in place in a well-known manner by clamp-bolts at 14^a, 14^b; in the drawing, however, only one such collar-member or part is shown. By loosening and shifting the retainer-collar 14, sliding it back against the similarly constructed and removable retaining-collar 15, the driver-member B being thus released, may then be slid longitudinally sufficiently far forward to disengage from the member D. If, now, the collar 15 be removed, the driver B may then be slid forward and removed from the grinder-shaft proper. The collar 15 is made to fit in a groove, at 15^a, turned in the driver B, and thus furnish a positive stop against the driver sliding too far outwardly.

In the present instance I have shown the forward grinder member D made of a considerable length so as to be directly supported at the forward end thereof by the forward bearing b¹ and at the rearward end thereof by the second bearing b². In some cases this manner of building up the entire length of the grinder shaft S will be found desirable, and it will, therefore, be understood that in practice the grinder may be constructed wholly of the relatively long members, as D, or that it may in some cases be made up of shorter members, as for instance, such members as D¹ and D², which form a pair extending from said second bearing b² to the third bearing b³. The rearward end of the grinder member D² is shown engaging with a cylindrical tubular bearing piece N, the driving connection being formed through interlocking shoulders at 12. Similarly, the forward members D¹ of said pair is shown having a driving engagement with the rearward member, D², through the interlocking shoulders at 12^a.

From the bearing b³ to the rear carrier member C, the grinder S is shown built up of short grinder members, as D³, and of the preferred form more fully illustrated in Figs. 6 and 7. Owing to the very short length of this style of the grinder members they are properly designated as collars while the longer ones may be designated as tubular members. The collar-form grinder-members D³ are shown provided with radially-disposed faces, f, f, whereby they interlock with the driving engagement already

mentioned. Each collar, or grinder-member D³, is preferably provided with a plurality of teeth, as t, t, (Figs. 6 and 7) of a suitable form; these grinder-teeth are shown so located, two on each collar, that the collars assemble interchangeably in any order, with the teeth t always in a spiral relation on the shaft S, as in Fig. 1. This spiral arrangement is, or may be, the same as shown on that longer grinder-member D, as clearly indicated in Figs. 1 and 4.

Another feature of my present improvements relates to the guide-bar for alining the grinder-members with each other and with the driver-member and the rear carrier-member, thus acting after the manner of a dowel, or doweling-rod, in connection with tensioning or clamping devices supplemental thereto. In practice, almost any sectional form of doweling-rod may be used, especially when the function of this rod is mainly as a guide or assembling-bar, to prevent any of the members—as D, D¹, D², D³—from being shifted out of line through the jamming which sometimes occurs by the melting down of the slag, or in connection with the manner in which the power is applied for operating the grinder. One suitable form of this guide or rod is illustrated in Figs. 5 and 9, it being there shown as a three-winged bar R: this bar should be small enough to slide freely through and revolve in the several grinder members, including the forward member B, and to enter the rearward member C. The rod R being wing-shaped, its use provides spaces or channels, as n, Fig. 5, in which the air may flow directly against the inner surfaces of the tubular grinder members, whereby to keep these from becoming too greatly heated. When the rotatable air-passage rod R is drawn out, any of the grinder members, such as D, may be lifted out, the grinder being first turned to bring the driving-lugs or faces, as 4^a, into a vertical position, as already mentioned. But when it is necessary to first remove the collar-form, D³, of grinder-member, the guide-bar should be removed and also, if need be, the driver B slid forward, which may be done in the manner before explained. For enabling the winged-bar R to also serve as a tensioning rod, for clamping together the assembled grinder-members into driving engagement with each other, the rearward end of the rod R is shown in Fig. 9 formed with the threaded end 31 which screws into the nut 5^b, while the forward end at 31^a of said rod is threaded to engage with the nut H which draws against the driver-member B, as illustrated at the left-hand in Fig. 9. Thus the screw-threaded devices in connection with the described coacting parts, operate for clamping the grinder-members together and also to draw the driver-member and the rear-carrier toward each other and

130

into driving engagement with the forward and rearward grinder-members, respectively. The nut H may have a guard-cap, as 32, with air-inlets, 32^a. The openings 32^a also permit the insertion of a small steel rod which may be run into the air-channels for dislodging obstructions formed from time to time by the gradual accumulation of fine cinder working in between the grinder members, these being usually made of unfinished iron castings. One or more detent screws, as 33, may be used for detaining the nut H from being jarred loose during the operation of the mechanism.

15 When it is not desired to make the guide-bar and tensioning rod in a single piece, a plain tube, as T, Fig. 1, may be used as the guide or doweling bar, and a separate bolt, as 35, may be screwed into the nut 5^a of 20 the rear carrier C, while a nut, H¹, (similar to nut H) is screwed onto the forward end, as indicated at the left-hand in Fig. 1. As a means for enabling the operator to enter the point of the bolt 35 into said nut 5^a, 25 wings i (Fig. 1) are shown located on this bolt for guiding or centering the same in the tube T, while permitting the air currents to freely flow through the tubes. The nut H¹ is shown provided with the guard 30 32 and air passages such as indicated in Figs. 9 and 10. The tube T is also shown internally threaded at 36, in its forward end, so that a screw may be inserted for drawing out the tube by means of a powerful 35 screw-jack, or other suitable tool (not shown) should the tube become stuck in the grinder-members by the over-heating of these parts, as will sometimes occur.

In some instances, the bolt 35 may be omitted while retaining the tube T; in such cases the tube T may extend outwardly from the forward end 19 of the driver B, as indicated in Fig. 12, and may have an external thread 36^a engaging directly into the nut H², 40 which is thus similar to the nut H in all material respects. In this arrangement of the tube, the rearward end may be reduced and formed into a screw, as 31^b, Fig. 14, while several air passages, as n², are formed 45 in the tube wall. With the tube ends formed as here described, the tube T may be substituted for the rod R, in Fig. 9, without other change, and without otherwise affecting the organization of the grinder as a 50 whole. Instead of reducing the tube T as in Fig. 14, the carrier C may be internally threaded as at 5^c, Fig. 13, and the tube T may be threaded to screw directly into the carrier, as there shown; in this case, the 55 forward end of the tube should be arranged as in Fig. 12, with the result of making this tube constitute a guide-bar and also a tensioning member, but in all these cases avoiding the guide-bar from becoming a driving- 60 shaft for the grinder-members, which them-

selves, in this system, constitute the driving shaft of the apparatus.

A further modification of the guide-bar construction is shown in Fig. 11, in which the tube T is shown having external air-passages, n (as in Fig. 5) while also having a central passageway, n⁵. This form of the guide-bar may be used in connection with the central bolt 35; or the forward end may be threaded as in Fig. 12, while the rearward end is formed as in Fig. 14.

Having thus described my invention, I claim:

1. In a clinker-grinder for furnaces, the combination with a tubular rotatable driver-member having a driving face on the inner end thereof, of actuating means for rotating the driver-member, a plurality of hollow and longitudinally separable grinder-members having one through another a driving engagement with the driver-member, and a non-driving guide bar extending through the grinder members for holding these members in working alinement, and having a passage for a current of air, substantially as described.

2. In a clinker-grinder for furnaces, the combination with a tubular rotatable driver-member having a driving face on the inner end thereof, of actuating means for rotating the driver-member, a plurality of hollow and longitudinally separable grinder-members having one through another a driving engagement with the driver-member, and a guide bar arranged for removal independently of the removal of the driver-member and extending through the grinder members for holding these members in working alinement, and having a passage for a current of air, substantially as described.

3. In a clinker-grinder for furnaces, the combination with a tubular rotatable driver-member having a driving face on the inner end thereof, of actuating means for rotating the driver-member, a plurality of hollow and longitudinally separable grinder-members having by an interlocking engagement one through another a driving engagement with the driver-member, a guide bar removably supported within and extending through the grinder members for holding these members in working alinement, and having a passage for a current of air, and a screw-threaded tensioning device for clamping the grinder-members.

4. In a clinker-grinder for furnaces, the combination with a tubular rotatable driver-member having a driving face on the inner end thereof, of actuating means for rotating the driver-member, a plurality of hollow and longitudinally separable interlocking grinder-members having one through another a driving engagement with the driver-member, a guide bar removably supported within and extending through the grinder-members,

- members for holding these members in working alinement, and having a longitudinal passage for a current of air, and tensioning means in operative connection with said 5 guide bar for clamping together the grinder-members by the aid of the guide-bar as a tension-member, substantially as described.
5. In a clinker-grinder for furnaces, the 10 combination with a tubular rotatable driver-member having a driving face on the inner end thereof, of actuating means for rotating the driver-member, a plurality of hollow and longitudinally separable inter-engaging 15 grinder-members having one through another a driving engagement with the driver-member, a non-driving guide bar extending through the grinder members for holding these members in working alinement, and having a longitudinal passage for a current 20 of air, and screw-threaded members engaging threaded ends of the guide-bar whereby to clamp and release the grinder-members, substantially as described.
6. In a clinker-grinder for furnaces, the 25 combination with the tubular driver-member having a driving face on the inner end thereof, actuating means operatively carried thereon, of a composite tubular grinder-shaft having its forward member engageable with 30 the driver-member, an air-passage guide-bar located within the grinder-shaft and removable independently of the driver-member, a shiftable driver-retainer for releasing the driver-member and so permitting the 35 withdrawal of this member by a limited movement out of engagement with the grinder-shaft, and a removable device for permitting the complete withdrawal of the 40 driver-member.
7. In a clinker-grinder for furnaces, the 45 combination with the tubular driver-member having actuating means operatively carried thereon and having a driving-face on the inner end thereof, of a composite tubular 50 grinder-shaft having its forward member provided with driving-faces engageable with said faces of the driver-member, a guide-bar having a longitudinal air passage and located within the grinder-shaft and removable independently of the driver-member, a shiftable driver-retainer for releasing the driver-member and so permitting the withdrawal of this member longitudinally 55 out of engagement with the forward member of the grinder-shaft, and a removable retainer-collar for permitting the complete withdrawal of the driver-member out of the grinder-shaft.
8. In a clinker-grinder for furnaces, the 60 combination with the tubular driver-member having actuating means operatively carried thereon and having transverse driving-faces on the inner end thereof, of a composite tubular grinder-shaft having its forward member provided with driving-faces 65 engageable with said faces of the driver-member, a guide-bar having a longitudinal air passage and located within the grinder-shaft and rotatable therein, and removable independently of the driver-member, screw-threaded devices substantially such as described arranged for clamping the grinder-members into driving engagement with each other and clamping one of these into engagement with the driver-member, a shiftable driver-retainer for releasing the driver-member and so permitting the withdrawal 70 of this member longitudinally out of engagement with the forward member of the grinder-shaft, and a removable retainer-collar for permitting the complete withdrawal 75 of the driver-member out of the grinder mechanism.
9. In a clinker-grinder for furnaces, the 80 combination with the tubular driver-member having actuating means operatively carried thereon and having a driving-face on the inner end thereof, of a composite tubular grinder-shaft having its forward member engageable with said faces of the driver-member, a guide-bar located within the grinder-shaft and rotatable therein, and removable independently of the driver-member, a retainer-device on the driver-member and removable for permitting the complete withdrawal of the driver-member out of the 85 grinder mechanism.
10. In a clinker-grinder for furnaces, the 90 combination with the tubular driver-member having actuating means operatively carried thereon and having transverse driving-faces on the inner end thereof, of a composite tubular grinder-shaft having its forward member provided with driving-faces 95 engageable with said faces of the driver-member, a guide-bar having a longitudinal air passage and located within the grinder-shaft and rotatable therein, and removable independently of the driver-member, screw-threaded devices comprising a nut at the forward end of the driver-member, and arranged in connection with the driver-member and guide bar for clamping the grinder-members into driving engagement with each other and clamping one of these into engagement with the driver-member, and a shiftable driver-retainer for releasing the driver-member and so permitting the withdrawal of this member longitudinally out of engagement with the forward 100 member of the grinder-shaft.
11. In a clinker-grinder for furnaces, the 105 combination with the tubular driver-member having actuating means operatively carried thereon and having transverse driving-faces on the inner end thereof, of a composite tubular grinder-shaft having its forward member provided with driving-faces 110 engageable with said faces of the driver-member, a guide-bar having a longitudinal air passage and located within the grinder-shaft and rotatable therein, and removable independently of the driver-member, screw-threaded devices substantially such as described arranged for clamping the grinder-members into driving engagement with each other and clamping one of these into engagement with the driver-member, a shiftable driver-retainer for releasing the driver-member and so permitting the withdrawal 115 of this member longitudinally out of engagement with the forward member of the grinder-shaft, and a removable retainer-collar for permitting the complete withdrawal 120 of the driver-member out of the grinder mechanism.
12. In a clinker-grinder for furnaces, the 125 combination with the tubular driver-member having actuating means operatively carried thereon and having transverse driving-faces on the inner end thereof, of a composite tubular grinder-shaft having its forward member provided with driving-faces engageable with said faces of the driver-member, a guide-bar having a longitudinal air passage and located within the grinder-shaft and rotatable therein, and removable independently of the driver-member, screw-threaded devices substantially such as described arranged for clamping the grinder-members into driving engagement with each other and clamping one of these into engagement with the driver-member, a shiftable driver-retainer for releasing the driver-member and so permitting the withdrawal 130 of this member longitudinally out of engagement with the forward member of the grinder mechanism.

mechanism independently of the grinder-shaft.

11. In a clinker-grinder for furnaces, a composite tubular grinder-shaft comprising a series of grinder-members shaped and arranged for interlocking driving-engagement with each other, in combination with a rotatable tubular driving-member at the forward end in driving-engagement with a 10 grinder-member and a rotatable tubular carrier-member at the rear end of said shaft, an air-passage guide-bar rotatively and removably located within the grinder shaft, for alining the grinder-members, clamping 15 means supplemental to said guide-bar and arranged for drawing the driver-member and carrier member one toward the other and thereby clamping together the grinder members, bearings for the driver-member and for the 20 carrier-member whereby these members are supported independently of each other, and a draft-conduit in connection with the interior of the carrier-member.

12. In a clinker-grinder for furnaces, a composite tubular grinder shaft comprising a series of collar-form grinder-members shaped and arranged for interlocking driving-engagement with each other, in combination with a rotatable tubular driver-member at the forward end in driving-engagement with a 25 grinder-member and a rotatable tubular carrier-member at the rear end of said shaft, an air-passage guide-bar rotatively and removably located within the grinder shaft for alining the grinder-members, and clamping means supplemental to said guide-bar and comprising a concentrically located nut in the interior of said carrier-member, and arranged for drawing the driver-member and carrier-member one 30 toward the other and thereby clamping together the grinder members, and a draft-conduit rearward of and in connection with the interior of the carrier-member.

13. In a clinker-grinder for furnaces, a composite tubular grinder-shaft comprising a series of the described grinder-members shaped and arranged for interlocking driving-engagement with each other throughout the length of said shaft, in combination with a rotatable tubular driver-member at the 45 forward end and a rotatable tubular carrier-member at the rear end of said shaft, a

winged air-passage non-driving guide-bar removably located within the grinder shaft for alining the grinder-members, and clamping means supplemental to said guide-bar for drawing the driver-member and carrier-member one toward the other and thereby clamping together the grinder members, bearings for the driver-member and for the 50 carrier-member whereby these members are supported independently of each other, and a draft-conduit in connection with the interior of the carrier-member.

14. In a clinker-grinder for furnaces, a composite tubular grinder-shaft comprising a series of grinder-members having interlocking driving-engagement with each other, in combination with a rotatable tubular driver-member at the forward end and a 55 rotatable tubular carrier-member at the rear end of said shaft, an air-passage non-driving guide-bar within the grinder shaft for alining the grinder-members, and clamping means supplemental to and comprising the 60 said guide-bar and arranged for drawing the driver-member and carrier-member one toward the other and thereby clamping together the grinder-members, bearings for the driver-member and for the carrier-member 65 whereby these members are supported independently of each other, a draft-conduit in connection with the interior of the carrier-member, and a retainer device in operative connection with the driver-member 70 and shiftable for releasing this driver from the grinder-shaft.

15. In a clinker-grinder for furnaces, a tubular grinder-shaft comprising a series of the described collar-form grinder-members 75 arranged for interlocking driving-engagement with each other, in combination with a rotatable tubular driving-member at the forward end and a rotatable tubular carrier-member at the rear end of said shaft, a three-winged, air-passage, non-driving guide-bar removably located within the grinder shaft for alining the grinder-members, and clamping means supplemental to and comprising the said guide-bar and a 80 concentrically located nut in the interior of said carrier-member, and arranged for drawing the driver-member and carrier-member one toward the other and thereby clamping together the grinder-members.

OROSCO C. WOOLSON.
